2,166,458

CONNECTOR

Arthur A. Berndt and Homer C. Nycom, Chicago,
Ill., assignors to Electroline Company, Chicago,
Ill., a corporation of Illinois

Application November 11, 1937, Serial No. 174,006

3 Claims. (Cl. 174—94)

The invention relates to connectors for conductors and the like used in electrical transmission and which have one or more wires of higher tensile strength than the others.

- 5 An object of the invention is to provide an electrical connector which will rapidly and effectively join conductors and which will have a high conductivity equal to or better than that of the wire joined thereby.
- 10 It is a further object of the invention to provide a fitting such as a connector having means for securely and firmly gripping and holding a wire and also having auxiliary gripping means acting conjointly therewith for insuring good electrical contact therebetween.

15 A further object is to provide a connector of the type above described having main and auxiliary gripping members, wherein one set of gripping members is wedged into contact with the conductor by the tapering end walls of the housing and wherein the other set of gripping members is wedged into contact with the conductor by means independent of the housing.

20 A further object of the invention is to provide a connector which will be simple in construction, economical to manufacture and which will be well adapted for the purposes described.

25 With these and various other objects in view, the invention may consist of certain novel features of construction and operation, as will be more fully described and particularly pointed out in the specification, drawing and claims appended hereto.

30 In the drawing which illustrates an embodiment of the invention and wherein like reference characters are used to designate like parts—

35 Figure 1 is an elevational view, parts being shown in section, of a connector embodying features of the invention;

40 Figure 2 is a rear elevational view of the electrical-contact gripping member;

45 Figure 3 is a longitudinal sectional view of the member shown in Figure 2; and

50 Figure 4 is a sectional view, parts being shown in elevation, of a modified form of connector embodying features of the invention.

The improvements of the invention materially increase the electrical conductivity of connectors of the type shown in the Berndt Patent No. 1,955,528 granted April 17, 1934 by means of an auxiliary gripping member which is purposely made of metal offering low resistance to the flow of the electric current therethrough and which has a limited value of compressive ability. The 55 wire or conductor is securely gripped by the usual

gripping members of relatively hard, high resistance metal which have as their primary function the holding or gripping of the wire, whereas, the flow of electric current from the wire to the housing of the connector is taken care of by the low 5 resistance gripping members.

Referring to Figure 1, the connector consists of a tubular housing or casing 12 of any suitable metal having good conductivity, such as copper, steel or ferrous alloy, and which is provided at 10 each end thereof with tapering end portions 13. Each tapering end portion is formed with an opening 14 of considerably smaller diameter than the size of the cylindrical portion of the casing. Located within the casing and more particularly 15 within each tapering end portion thereof is a one-piece, multi-segment gripping member designated in its entirety by 15 which is purposely made of soft low resistance metal to facilitate the flow of the electric current therethrough. The member 15 is provided with a central bore 16 for receiving the wire or strand 18, the said bore being smooth throughout its length and the tapering exterior of the member also being smooth and conforming to the slope of the end portions 20 of the casing. The member 15 is approximately divided into two parts as a result of the cuts located diametrically opposite each other, the lower of said cuts, as shown in Figure 2, forming a recess 20 which extends for the length of the member, whereas, the upper of said cuts forms the slot 21 and completely separates the opposed portions of the member. In the absence of the slot and recess the member would have absolutely no compressive ability but as a result thereof the 30 said low resistance gripping member has limited compressive ability and will therefore grip the wire or conductor sufficiently to insure a good contact between the parts.

For securely holding the wire within the connector the invention provides additional gripping members 22, their main function being to securely hold the wire to the casing and therefore these members are formed of hard, high resistance metal. As shown in Figure 1, the members are in the form of segments, each having a tapering exterior and providing teeth 23 for engaging with the wire conductor inserted within the connector. The segments are preferably held together to form a unit by the resilient spring 45 24, which seats within the groove 25 formed on the exterior surface of each segment. The mechanical gripping members are disclosed as comprising a plurality of separate independent segments only for purposes of illustration, it being 50 55

understood that a one-piece multi-segment member or other form of gripping means may be substituted therefor. A floating sleeve 26 is located within each end of the casing 12, back of the gripping members 15, respectively, each sleeve receiving a set of the high resistance mechanical grips and providing a tapering interior surface with which the grips engage. The forward end of each floating sleeve is flared as at 27, this end having contact with the one-piece multi-segment member 15. The rearward end of each sleeve has a cylindrical portion 28 adapted to receive the reduced end of the spring seat 30. The shoulder 31, formed as a result of the increased diameter of the spring seat 30 toward its open end, forms a stop, limiting the movement of said member within sleeve 26. A coil spring 32 is confined between the opposed spring seats 30 which have their open ends directed toward each other. It will be observed that the spring seats do not contact the mechanical grips 22 but instead apply pressure to the floating sleeves 26 which are accordingly forced outwardly toward the electrical-contact gripping members 15.

Upon the insertion of a conductor within an opening 14 of the casing 12 the said wire will pass through the bore 16 of the member 15 which will have a tight sliding fit with said wire. Further insertion of the same will cause the forward end 30 of the wire or conductor to enter the passage provided by the gripping members 22. These gripping members will be carried as a unit by the said conductor toward the spring seat 30, whereupon further movement inwardly of the wire will force 35 the same completely through the passage so that the teeth 23 have engagement with the exterior surface of the wire at the forward end thereof as shown more particularly in Figure 1. When an attempt is made to withdraw the conductor 40 from the casing 12 the parts comprising the present connector will travel outwardly along with the wire until the one-piece member 15 is brought into contact with the tapering end portion of the casing. As a result thereof movement 45 is likewise prevented of the floating sleeve 26 which results in bringing the mechanical grips 22 into firm and secure contact with the tapering interior wall of the said sleeve. Outward movement of the conductor is thereby prevented and as the tension on the conductor increases, the holding power of the mechanical grips likewise increases, it being clear that the segments 22 will bite farther into the metal of the conductor as the said segments are forced into the restricted portion 50 of the sleeve. The tension of the conductor is transmitted from the sleeve to the one-piece multi-segment member 15 which is accordingly forced into firm and secure contact with the tapering walls of the casing. This causes the member to 55 contact, the slot 21 gradually closing, bringing the surfaces of the opposed portions together, and the member thereby increases its grip on the conductor, which, however, is limited to the extent of the slot 21 closing. This compressive ability 60 of the member 15 is however sufficient to insure good electrical contact. The flow of the current is facilitated through this member due to the fact that it is formed of a soft, low resistance metal.

In the modified form of the invention shown in Figure 4, the connector can be reclaimed. In other words, it is possible for the workman to release the gripping action of the mechanical grips and withdraw the wire from the connector. Two 75 separable casings are employed in this form of

the invention as indicated by numerals 35 and 36, each casing having reduced end portions 37 and 38, respectively. In the formation of these casings, the portions 37 are formed first and after the various elements of the connector are inserted within the casing, the opposite ends thereof are swaged down to form the tapering portions 38. Accordingly, assembling consists in first inserting within each casing the electrical-contact gripping member 40 which is substantially as shown in Figure 2, being formed of soft low resistance metal having a recess formed longitudinally therein and also a longitudinal slot to impart a limited value of compressive ability to the member. However, integral with each member 40 is an extension 41 which projects through the opening in this end of the casing. The extensions 41 each have an inspection opening 42 and the said extensions are suitably connected together as by welding so that the casings 35 and 36 are joined through the low resistance gripping members 40.

The mechanical gripping means comprising the segments 43 of hard high resistance metal, having teeth 44, are positioned in the opposite end of each of the casings and are retained together as a unit by resilient means 45. The segments have a tapering exterior and are in all respects similar to the segments 22 described in connection with the modification of Figure 1. As shown with respect to casing 35 the mechanical grips are resiliently forced into contact with the tapering walls of portion 38 by a coil spring 46 which is confined between the said segments and a washer 47. Said washer is retained in position by means of stops 48 punched in the casing 35. With respect to casing 36 the washer is omitted and these alternative forms are shown merely for purposes of illustration as either form or both may be used in a connector.

In using the form of connector shown in Figure 4 the wire or conductor is inserted completely through each casing, thus forcing the forward end of the said conductor into the bore provided by its respective gripping member 40 until the extreme end of the same is visible to the operator by looking through the inspection hole 42. When the proper size conductor is used the same has a relatively tight sliding fit with respect to the bore in the gripping members 40 which insures good electrical contact and the flow of the current takes place from the conductor through the members to the other conductor. In the act of inserting a wire the mechanical grips will be automatically separated, permitting passage of the wire through the casing. The coil spring will however maintain these grips in their particular end of the casing and when tension is placed on the conductor the gripping members will bite into the wire, providing a secure and firm connection which increases in holding power as the tension of the wire is increased.

In this form of the invention the connector can be reclaimed as it is possible to insert a reclaiming tool in the ends of the casings and release the mechanical grips which thereupon free the conductor.

The invention is not to be limited to or by details of construction of the particular embodiment thereof illustrated by the drawing, as various other forms of the device will of course be apparent to those skilled in the art without departing from the spirit of the invention or the scope of the claims.

What is claimed is:

1. A connector for connecting wires, comprising a pair of casings, each having oppositely directed tapering end portions, means connecting the casings including a gripping member having location within each casing and adapted to contact the tapering end walls of one end thereof, each gripping member having an opening in the same for receiving a wire inserted within its casing, and additional gripping means within each casing for also gripping and holding the end of the wire inserted within the same. 5
2. A connector for connecting wires, comprising a pair of casings each having oppositely directed tapering end portions, means connecting the casings including a gripping member having location within each casing and adapted to contact the tapering end walls of one end thereof, each gripping member having an opening in the same for receiving a wire inserted within its casing, additional gripping means within each casing including segments of wedge-shape for also gripping and holding the end of the wire within its respective casing, said segments having contact with the tapering walls of the other end 10 portion of its casing, and resilient means main- 15
10. taining each gripping member and the said additional gripping means properly located within the casing. 15
3. A connector for joining wires, comprising a pair of casings each having oppositely directed tapering end portions, means connecting the casings including a gripping member located within each casing and having contact with the tapering end walls of one end thereof, each gripping member being formed of soft low resistance metal and 10 having an opening therein for receiving the end of a wire extending within its respective casing, whereby the connecting means also aids in the flow of current from one wire to the other, additional gripping means in each casing including 15 segments of wedge-shape formed of hard high resistance metal for also gripping and holding the end of the wire within its respective casing, said segments having contact with the tapering walls of the other end of its casing, and resilient 20 means within each casing maintaining the gripping member and said additional gripping means properly located. 20

CERTIFICATE OF CORRECTION.

Patent No. 2,166,458.

July 18, 1939.

ARTHUR A. BERNDT, ET AL.

It is hereby certified that error appears in the printed specification of the above numbered patent requiring correction as follows: Page 2, first column, line 60, for the word "contact" read contract; and second column, line 9-10, for "eletrrical-contact" read electrical-contact; page 3, first column, line 25, claim 2, for "reslent" read resilient; and second column, line 4, claim 3, for "conector" read connector; and that the said Letters Patent should be read with this correction therein that the same may conform to the record of the case in the Patent Office.

Signed and sealed this 19th day of September, A. D. 1939.
